WINDOW STRUCTURE

Speros Carvour, Jersey City, N. J.

Application January 27, 1934, Serial No. 708,664

10 Claims. (Cl. 20—48)

The object of the present invention is to provide a novel form of window structure, including a vent member that can be opened laterally to any degree desired, and the opening can be divided between opposite sides of the window or located entirely at one side, as may be desired.

Another object is to provide such a vent member in a sash which itself is movable to an open and closed position, and when opened the vent member is locked in closed position, thus providing means for ventilation, while in effect locking the window against being tampered with from the outside.

A still further object is to provide in connection with this mechanism a third ventilating means which may be in the form of a transom and which is automatically opened when the sash is elevated.

In the accompanying drawings:

Figure 1 is an inside elevation of one embodiment of the invention.

Figure 2 is an exterior view in elevation of the same.

Figure 3 is a vertical sectional view on the line 3—3 of Figure 1, showing the window completely closed.

Figure 4 is a similar view but showing the window sash raised and the transom opened.

Figures 5 and 6 are sectional views on the lines 5—5 and 6—6 of Figure 1.

Figure 7 is a view similar to Figure 5, but showing the vent member partially opened.

Figure 8 is a detail vertical sectional view on the line 8—8 of Figure 3.

Figure 9 is a detail cross sectional view on the line 9—9 of Figure 8.

Figure 10 is a detail perspective view of the supporting and guiding member of the sash frame.

In the structure disclosed, a window frame 11 is provided, which may be of any suitable character, and either of wood or metal. It includes vertical side walls 12 having guideways 13 for a vertically movable sash frame. This sash frame includes an upper cross rail 14, a lower cross rail 15 and vertical side bars 16 connecting the same and slidably mounted in the guideways 13.

Above this sash frame there is pivotally mounted an upper window member shown in the form of a transom 17, the pivot supports therefor being designated 18 and being preferably located on the outer sides of the guideways 13, as will be clear by reference to Figures 3 and 4. This transom 17 is provided on its inner side with cam tracks 19 which lie in the path of the upper cross

rail 14, as will be clear by reference to Figure 3. Hence when the sash frame is raised, as shown in Figure 4, the cross rail 14 striking the cam tracks 19, will cause the transom to swing to open position, this affording ventilation at the top of the window.

The space within the sash frame 14—16 is adapted to be closed by a vent member consisting of sash sections 20. These sections preferably comprise suitably glazed-in frames 21 hinged at 10 their adjacent edges, as shown at 22, the member thus being capable of lateral folding as will be clear by reference to Figure 7.

In order to support this vent member, the upper cross rail 14 of the sash frame is provided with a suitable trackway and guide. Thus in the present form of construction, this consists of a metal channel piece 23 carried by the cross rail 14, and having its lower portion slotted, as shown at 24 with inturned marginal flanges 25. Hangers 26, pivotally connected with the upper outer corners of the sections 20 are suspended from rollers 27 that ride within the channel bar behind said flanges 25. The lower end of the vent member also preferably is guided, and to this end a suitable guideway 28 is provided on the upper side of the lower rail 15. The outer corners of the vent member sections 20 have depending guide pintles 29 that operate in said guideway 28 and these pintles may also carry supporting rollers 30 that ride on the walls of the guideway. A suitable locking bolt 31 that engages in said guideway 28 or other socket, serves to hold the sections 20 in aligned or closed position, and a finger piece 32 may be provided on the inner side of one of the sections 20 for laterally moving the same.

By reference particularly to Figures 2, 3 and 4, it will be noted that there is a bar 33 that extends across the space between the side bars 12 of the window frame and to which said cross bar 33 is secured. This bar 33 lies above the top edge of the sections 20 of the vent member when the sash frame is in its closed position, as illustrated in Figures 2 and 3. But when the sash frame is elevated, then the cross bar 33 is located in advance of the upper portions of said sections 20 and constitutes a means for preventing the lateral movement of the sections.

It will be understood that the sash, which includes the sash frame and the vent member, may be suitably counterbalanced by weights 34 having cable connections 35 with the sash frame and operating in the manner normal to window structures.

Considering now the operation of the structure

it will be noted that when the sash is closed, as illustrated in Figures 1, 2 and 3, by unlatching the vent at 31, it may be moved laterally and folded to a more or less degree as desired and as indicated in Figure 7, the vent member moving under the cross bar 33. Ventilating openings may thus be created on opposite sides of the vent member and of any extent desired, or the vent member can be moved to one side or the other of the sash frame. If only a small amount of ventilation is desired and the window kept in a condition to prevent being tampered with from the outside, the vent member may be closed and the sash slightly raised. When this is done, as shown in Figure 4, an opening is created below the sash and the vent members being now behind the cross bar 33, the latter acts as a lock which prevents the same being opened even if a person can thrust his hand beneath the sash and reach the lock 31. Depending on the amount of elevation of the sash, the transom 17 can either be left closed or be opened. In other words if the sash is raised sufficiently the transom may be opened, thus providing for ventilation at the top of the window.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention. In this connection it is to be understood that the disclosure is simply for explanatory purposes, and that the structural parts may be altered in various ways.

What I claim is:

1. In a window structure, a vertically slidable sash, a laterally opening vent member carried by and movable with the sash and operable when the sash is closed, and means for preventing the lateral opening of the vent member when the sash is in a predetermined open position.

2. In a window structure, a vertically slidable sash, a laterally opening vent member carried by and movable with the sash, and means for preventing the lateral opening of the vent member when the sash is in an elevated position.

3. In a window structure, a vertically slidable sash, a laterally opening vent member carried by and movable with the sash, and an obstruction against the lateral movement of the vent member, said vent member being movable to a position behind the obstruction on the vertical opening movement of the sash.

4. The combination with a window frame, of a vertically sliding sash frame in the window frame, a foldable vent member comprising hingedly connected sections having slideable mountings in the sash, and a bar across the frame, said vent member being movable to and from a position behind the bar and when in such position, said bar constituting means for preventing the folding movement of the vent member.

5. The combination with a window frame, of a vertically sliding sash frame in the window frame, a foldable vent member comprising hingedly connected sections having slideable mountings at their

outer upper and lower corners in upper and lower portions of the sash frame respectively, said mountings moving towards and from each other on the lateral movements of the sections, and a bar across the upper portion of the window frame and in advance of the path of the window sash frame, said vent member when closed moving to a position behind the bar when the sash is opened and thus locking the vent member against an opening movement.

6. In a window structure, the combination with a vertically sliding member movable upwardly from a closed position and a pivotally mounted member closing the space above said member when in its lowered closed position, of means for causing the swinging member to swing when the sliding member is slid upwardly to its open position.

7. In a window structure, the combination with a window frame, of a vertically movable sash member in the lower portion thereof, an outwardly opening transom member pivotally mounted in the frame above the sash member and closing the space above it, and means operated by the sash member in its upward opening movement to effect the opening movement of the transom member.

8. In a window structure, the combination with a window frame, of a vertically movable sash member in the lower portion thereof, an outwardly opening transom member pivotally mounted in the frame above the sash member and normally closing the space above it, and a cam member carried by one member and engaged by the other member on the upward opening movement of the sash member to cause the transom member to swing.

9. In a window structure, the combination with a window frame, of a vertically movable sash member in the lower portion thereof and movable upwardly to an open position, an outwardly opening transom member pivotally mounted in the frame above the sash member and closing the space above it when the sash is in its lowered position, and a cam member carried by the transom member and engaged by the sash member on its upward movement to cause the transom member to swing to open position.

10. In a window structure, the combination with a window frame, of a transom pivoted in the upper portion of the frame, a vertically sliding sash frame in the lower portion of the frame and having upper and lower rails provided with guideways, a vent member comprising hingedly connected sash sections having guides at their upper and lower corners movable in the guideways and permitting the lateral folding of the vent members and its adjustment in the sash frame, a holding bar across the window frame and behind which the vent member is located when the sash frame is elevated, said bar holding the vent member against folding and acting to prevent elevation of the sash when the vent member is folded, and means engaged by the sash frame when the vent member is closed and the sash is elevated to swing the transom to open position.

SPEROS CARVOUR.
